(57) **CLAIM**

The ornamental design for a flashlight, as shown and described.

DESCRIPTION

FIG. 1 is a rear and right side perspective view illustrating the rear, the right side and the top of the flashlight, showing my new design;

FIG. 2 is a front and left side perspective view illustrating the front and the left side thereof;

FIG. 3 is right side elevational view thereof;

FIG. 4 is a left side elevational view thereof;

FIG. 5 is a top elevational view thereof;

FIG. 6 is a bottom elevational view thereof;

FIG. 7 is a front plan view thereof; and,

FIG. 8 is a rear plan view thereof.

The broken line showing is for environmental purposes only and forms no part of the claimed design.
